UNITED STATES PATENT OFFICE

LEWEN R. NELSON, OF PEORIA, ILLINOIS

SPRINKLER

Application filed November 28, 1927. Serial No. 236,117.

This invention pertains to sprinklers of that type which includes a part for attachment to an upright standard or pipe discharging water under pressure, and a spray member pivotally supported on said part rotated by such water pressure.

An object of the invention is to provide a sprinkler head wherein the rotating spray member can always rotate freely even though 10 the part carrying it may become misshapen.

Another object is to furnish a sprinkler head of the type named wherein a ball and socket structure is employed as a bearing for one end of the spray member and so disposed 15 and arranged that though the other bearing for said member may be moved out of its normal position the said spray member may still rotate freely.

Still another object is to provide a spray 20 head wherein a rotating spray member has a ball and socket bearing at one end and a coned bearing at the other end arranged and adapted whereby a chance misshaping of the part carrying said spray member will not affect 25 the free rotation of the latter or destroy its effectiveness in distributing water.

In the appended drawing—

Figure 1 is a front elevation of my sprinkler head.

30 Figure 2 is a rear elevation of a spray member.

Figure 3 is a plan of the spray member, and

35 Figure 4 is a side elevation of the sprinkler head showing the front side of the said spray member.

I am aware of the prior art in devices of this type but am also familiar with the difficulties met with when such devices become 40 damaged in that when a slight disarrangement of the affair occurs the free rotation of the spray member is affected.

The sprinkler head of my invention is made up of a main body including a base portion 45 1 having a cavity 2 threaded to screw upon a standard, not shown, for supplying water under pressure. Further, the base is bored at 3 to communicate with said cavity 2 and is threaded to receive a screw 4 to be described 50 in detail presently. Extending from said

base is a pair of arms 5, for example, which curve outwardly and upwardly and meet in a yoke portion 6 provided with a bore 7 threaded to receive a plug 8 having, in this case, a slot 9 to receive a screw driver or similar tool, there being a jamb nut 10 carried by the screw adapted to engage the said yoke portion 6. In the inner end of the screw 8 is a conical recess 11 which receives the coned end of the stem 12 of the spray member denoted in general by the character 13.

The screw 4 has a bore 4' and one end extends beyond the base 1 in the direction of the screw 8 and is spherically rounded, the center of the bore 4' and the rounded surface 65 being substantially in line with the conical cavity 11 of said screw 8.

Said spray member 13 includes a body 14 hollowed out substantially as at 15, for example, and having a base portion 16 provided with a bore 17 to communicate with the bore 4' of said screw 4, the said base portion 16 of the member having in its lower surface a concavity 18 corresponding substantially to the curve of the exposed end of said screw 4, to receive the same.

In a study of Figure 1 it will be seen that the surface of the body 14 at the bottom of the hollow 15 curves from the base 16 upwardly and outwardly away from the center 80 of rotation so that water pressure upon said surface will cause spinning of the spray member on its supports which are the stem 12 and the spherically curved or ball surface of the screw 4.

The surfaces of the concavity 18 and of the screw 4 may directly engage throughout, or as in Figure 1 the rounded surface of the plug may be spaced from the surface of such concavity slightly so that the bearing may be 90 an annular one, reducing friction somewhat. The surface within the concave may, however, be otherwise formed so long as a free ball and socket effect is obtainable. By an adjustment of the screw 8, of course, the member 13 may be permitted as free movement as desired, any desired position of the plug being maintained by said jamb-nut 10.

The ball joint is located at the base portion 1 where there will be no likelihood of its being 100

damaged or thrown out of position while the other end of the member 13 is supported above at the screw 8. Now, since the said ball joint is below upon a rigid part of the sprinkler head it is clear that should the arms 5 become bent in any direction or in any way by accident so that the screw 8 is moved from its normal position as manufactured, with the axis of rotation of the member 13 at an angle to the bore 4', for example, the said member can 10 still rotate since the base portion 16 will merely move over the spherical surface of the screw 4 to a new position.

The spread of the conical recess 11 of the screw 8 may be preferably greater than the angle of the coned end of the stem 12, as shown, so that the point of said stem will seat in said recess for proper action even in extreme cases, the only adjustment necessary 20 being that of movement of the screw 8 to remove any pressure or binding and thus restoring free rotation.

The plug 4 while preferably a separate part of the structure for manufacturing reasons, 25 i. e., to more readily form the rounded surface that receives the member 13, may be omitted and said rounded surface may be formed on the body 1 and be equally effective.

On the other hand, it is preferable to make 30 the said screw 4 of hardened steel to withstand wear, besides in a measure reduce friction. Again, the stem 12 is preferably made of hardened steel for the same reasons, the same being held in a driving fit in a socket 35 12' of the member 13.

I claim:

A sprinkler head comprising a rigid body including a base having a passage and an arm a portion of which lies opposite and in 40 spaced relation to said base, a screw adjustably mounted in the said arm opposite said base and having a conical socket, a rotor, a stem inserted therein to engage in the said socket of the screw, the other end of the rotor 45 having a cavity, and a screw adjustably mounted in said base opposite the first named screw and having a spherically curved end to engage in the cavity of the rotor, there being a passage extending through the last named 50 screw communicating with the passage of the base, and there being a passage through that portion of the rotor having the cavity communicating with the passage of said last named screw.

55 In testimony whereof I affix my signature.
LEWEN R. NELSON.
